(57) **CLAIM**

The ornamental design for a combined container and overcap, as shown and described.

DESCRIPTION

FIG. 1 is a top, front, and right isometric view of the combined container and overcap showing our new design;
FIG. 2 is a front elevational view of FIG. 1;
FIG. 3 is a rear elevational view of FIG. 1;
FIG. 4 is a right side elevational view of FIG. 1;
FIG. 5 is a left side elevational view of FIG. 1;
FIG. 6 is a top plan view of FIG. 1;
FIG. 7 is a bottom plan view of FIG. 1;
FIG. 8 is a top, front, and right isometric view of the combined container and overcap showing a modified embodiment of our new design;
FIG. 9 is a front elevational view of FIG. 8;
FIG. 10 is a rear elevational view of FIG. 8;
FIG. 11 is a right side elevational view of FIG. 8;
FIG. 12 is a left side elevational view of FIG. 8;
FIG. 13 is a top plan view of FIG. 8; and,
FIG. 14 is a bottom plan view of FIG. 8.

The broken lines are included for the purpose of illustrating portions of the combined container and cap that form no part of the claim to the embodiment in which they are shown.
